(57) **CLAIM**

The ornamental design for a spinning reel rotor for fishing as shown and described.

DESCRIPTION

FIG. 1 is a perspective view of a spinning reel rotor for fishing showing the new design;

FIG. 2 is a front view of the spinning reel rotor for fishing of FIG. 1 showing the new design;

FIG. 3 is a rear view of the spinning reel rotor for fishing of FIG. 1 showing the new design;

FIG. 4 is a plan view of the spinning reel rotor for fishing of FIG. 1 showing the new design;

FIG. 5 is a bottom view of the spinning reel rotor for fishing of FIG. 1 showing the new design;

FIG. 6 is a right side view of the spinning reel rotor for fishing of FIG. 1 showing the new design;

FIG. 7 is a left side view of the spinning reel rotor for fishing of FIG. 1 showing the new design; and,

FIG. 8 is a perspective view of the spinning reel rotor for fishing of FIG. 1 showing the new design in an environment of use.

The broken lines in the drawings depict environment and form no part of the claimed design. The long-dash/short-dash broken lines indicate the boundary of the claimed design and form not part of the claimed design.

1 Claim, 8 Drawing Sheets
